AUXILIARY UNITS FOR OPERATING
POWER PLANTSGlenn B. Warren, Schenectady, N. Y., assignor
to General Electric Company, a corporation of
New York

Application August 24, 1935, Serial No. 37,704

1 Claim. (Cl. 103—6)

The present invention relates to auxiliary units for operating power plants and has for its object an improved construction and arrangement of such auxiliary units whereby a plurality of auxiliaries, such as blowers, pumps, and like appliances or accessories, are driven by a single motor or prime mover and united with such prime mover to form a unitary, compact structure which can be easily installed and transported as a whole.

For a consideration of what I believe to be novel and my invention, attention is directed to the following description and the claim appended thereto in connection with the accompanying drawings.

In the drawings Fig. 1 represents a perspective view of an auxiliary unit embodying my invention; Fig. 2 is a perspective view of certain elements of Fig. 1; Figs. 3 and 4 are diagrammatic views illustrating the auxiliary unit in combination with a boiler and other elements of a power plant; and Fig. 5 is a detail view of Fig. 1.

The arrangement shown diagrammatically in Fig. 3 comprises an auxiliary unit 10 for operating a power plant including a boiler 11, a main turbine 12, means including a gear 13 driven by the main turbine and a condenser 14 for the turbine. The auxiliary unit includes a motor or auxiliary turbine 15, a blower 16, a fuel pump 17, a boiler feed pump 18 and a lubricating pump 19. The blower and all the pumps are driven by the auxiliary turbine. The latter receives elastic fluid through a conduit 20 having a branch 21 including a valve connected to the boiler and another branch 22 including another valve connected to an intermediate stage 23 of the main turbine 12. The elastic fluid discharged from the auxiliary turbine is conducted by a conduit 24 to the condenser 14, which latter also receives the exhaust from the main turbine through a conduit 25. The inlet of the main turbine is connected to the boiler 11 by a conduit 26 including a valve 27. The blower has an inlet opening 28 for receiving air and is connected to the furnace of the boiler 11. The fuel pump is connected to the furnace by a conduit 30 and serves to force fuel into the furnace. The blower and the fuel pump together represent a means for conducting combustible material and air to the furnace. The boiler feed pump 18 is connected to the condenser by a conduit 31 and to the boiler by a conduit 32. During operation the boiler feed pump feeds the condensate from the condenser into the boiler. Broadly, the boiler feed

pump represents a means for conducting operating fluid to the boiler. The lubricating pump 19 has an inlet 33 for receiving lubricant and an outlet 34 connected by pipes 35, 36 and 37 to bearings 38 of the auxiliaries and bearings 39 of the main turbine. During operation, the lubricating pump forces lubricant to the different bearings.

In accordance with my invention the auxiliaries, that is, the blower, the pumps and the prime mover for driving them are united to form a single structure which can be easily transported as a compact unit and readily assembled together with other elements of a power plant. This feature of compactness is diagrammatically indicated in Fig. 4, showing the auxiliary unit 10 placed adjacent the boiler 11 and connected thereto by the three conduits 28, 30, and 32 for conducting air, fuel and operating fluid respectively to the boiler.

The structural arrangement of the auxiliary unit, as shown in Figs. 1 and 2, comprises a gearing having a casing 40 with a cover 41 secured thereto by bolts 42. A plurality of shafts, in the present instance a first shaft 43, a second shaft 44 and a third shaft 45, are supported by the casing 40. These shafts are connected by speed reducing gearings 46 and 47 respectively. The auxiliary turbine 15 has a wheel 48 secured to an overhung portion of the first shaft 43. By 30 an "overhung portion of a shaft" is meant a portion, the free end of which is not supported by a bearing. The casing of the turbine is secured to the gearing casing 40 by means of bolts 49. The turbine casing includes a valve chest 35 50 including valves and conduits 21 and 22 for conducting elastic fluid from an intermediate stage of a main turbine and from a boiler or elastic fluid generator respectively. The turbine exhausts into the conduit 24. The valves contained in the chest 50 may be controlled by means including a lever 51.

The blower 16 is of the centrifugal type and includes an impeller 52 secured to an overhung portion of the second shaft 44 facing away from the turbine wheel. The impeller 52 is contained within a casing 53 forming an inlet conduit 54 with the opening 28 and a scroll with a flanged outlet opening 55. During operation, air is forced into the inlet conduit 54 by the action of the impeller and is discharged through the flanged outlet opening 55. The casing 53 of the blower is secured to a flange of the gearing cover 41 by means of bolts 56.

In cases, as in the present instance, where the

auxiliary unit is driven by an elastic fluid turbine receiving elastic fluid from the main boiler, means must be provided for starting the boiler, that is, for supplying air to the furnace thereof before the main blower can be operated. The starting means in accordance with my invention comprises an independently driven auxiliary blower, in the present instance shown as a fan 57 driven by an electric motor 58. The motor driven fan is held on a support 59 welded to the casing 53 of the main blower 16. The scroll has an opening 60 (Fig. 5) near the flanged outlet opening 55 and the fan 57 is arranged to force air through the opening 60 in the direction of the flanged outlet opening 55, that is, along the path defined by the outlet portion of the scroll. A funnel or nozzle 61 is disposed adjacent the fan to increase the pressure of air forced towards the opening 60 during operation of the fan 57. The nozzle 61 is secured to a lateral extension 62 of the main blower casing 53. As stated before, the auxiliary blower represents a means for starting a boiler before the turbine driven main blower can be operated. During normal operation of the main blower the discharge of air from the scroll through the opening 60 is prevented by means including a valve member 61a for closing the compression nozzle 61. The third shaft 45 is driven from the second shaft through the reducing gearing 47 and indirectly from the first shaft 43 through the double reduction gearings 46 and 47. The right-hand portion of the shaft 45 is overhung and connected to a crank shaft 63 which forms a part of the feed pump 18. In a preferred embodiment, as shown in the present instance, the crank shaft 63 and the shaft 45 form a single integral element contained in an extension 64 of the gearing casing 40. The other elements of the feed pump are supported on the extension 64 and secured thereto by means of bolts 65. The pump has a cover 66 forming openings for receiving the inlet or suction conduit 31 and the outlet or discharge conduit 32. Other features of the boiler feed pump are more fully disclosed in the application of John H. Doran, Serial No. 30,085, filed July 6, 1935 and assigned to the same assignee.

The fuel pump 17 and the lubricating pump 19 are driven from a vertical shaft 67 connected to the free end of the horizontally disposed crank shaft 63 by a helical gearing 68. The gearing 68 is contained within a casing 69 secured to the ex-

tension 64 of the gearing casing 40 and provided with a removable end plate 70. The lubricating pump has a casing 71 welded to the extension 64 of the gearing casing and including a removable cover or end plate 72 with the discharge conduit 34. The inlet conduit 33 for the lubricating pump is disposed within the extension 64 so that during operation of the auxiliary unit, oil or like lubricant contained in the gearing casing is circulated by the lubricating pump to the different bearings of the auxiliaries and other apparatus, whence the lubricant may be returned to the gearing casing by conduit main (not shown).

The fuel pump 17 has a casing 74 with an inlet conduit 75 and the discharge conduit 30. The casing 74 is fastened to brackets 76 by means of bolts 77, the brackets being welded to the cylinder jacket of the boiler feed pump 18.

With my invention I have accomplished an improved construction and arrangement of auxiliary units for operating power plants. The unit forms a single, compact structure which can be easily transported when assembled and readily put in operation in connection with other elements of a power plant. All of the auxiliaries, that is, the blower and the pumps, are driven by a prime mover through the intermediary of a gearing which has a fabricated or welded casing supporting the different drive shafts and also supporting at least partly the casings of the various auxiliaries.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent in the United States is:

An auxiliary unit for operating a power plant including a gearing having a casing and a first, a second and a third shaft supported on the casing and having overhung portions, reducing gearing means connecting the shafts, a motor having a rotor secured to the overhung portion of the first shaft, a blower having an impeller secured to the overhung portion of the second shaft, and a boiler feed pump driven from the overhung portion of the third shaft, all of the aforesaid elements being united to form a single structure transportable as a unit.

GLENN B. WARREN.
